[57] CLAIM

The ornamental design for a fast food tray, as shown and described.

DESCRIPTION

FIG. 1 is a top perspective view of a fast food tray showing my new design;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevational view thereof; the elevational views of FIGS. 5 and 6 alternate about the tray;

FIG. 7 is a perspective view thereof; with a carton formed of one tray inverted over another tray; shown as an environmental use of the tray;

FIG. 8 is a top perspective view of a second embodiment of the tray in FIG. 1;

FIG. 9 is a bottom perspective view of FIG. 8;

FIG. 10 is a top perspective view of a third embodiment of the tray in FIG. 1; and,

FIG. 11 is a top perspective view of a fourth embodiment of the tray in FIG. 1.

The bottom perspective views of the third and fourth embodiments (FIGS. 10 and 11) are similar to the corresponding view of the second embodiment (FIG. 9).
